UNITED STATES PATENT OFFICE.

EDWARD FERRISS, OF CARSON LAKE, MINNESOTA.

ATTACHMENT FOR GAS-ENGINE RADIATORS.

1,341,419.

Specification of Letters Patent. Patented May 25, 1920.

Application filed December 14, 1918. Serial No. 266,802.

To all whom it may concern:

Be it known that I, EDWARD FERRISS, a citizen of the United States, resident of Carson Lake, county of St. Louis, State of Minnesota, have invented certain new and useful Improvements in Attachments for Gas-Engine Radiators, of which the following is a specification.

My invention relates to an attachment for the radiator of a gas engine, particularly adapted for automobiles, trucks and the like, and the object of the invention is to provide means for maintaining a circulation of air through the radiator and regulating the volume of such air when the machine is in motion and creating temporarily a closed chamber with a means for heating the air in this chamber to prevent too rapid cooling or freezing of the radiator when the machine is standing still.

A further object is to provide an attachment which can be readily applied to a radiator of the type described with comparatively little inconvenience and expense. Other objects of the invention will appear from the following detailed description.

The invention consists generally in various constructions and combinations, all as hereinafter described and particularly pointed out in the claims.

In the accompanying drawings forming part of this specification,

Figure 1 is a view, partially in section, of the forward portion of an automobile, showing the hood and radiator and my attachment mounted thereon,

Fig. 2 is a similar view, showing the air controlling means open to allow the free circulation of air through the radiator,

Fig. 3 is a front view of Fig. 1,

Fig. 4 is a horizontal sectional view through the attachment.

In the drawing, 2 represents the forward portion of the frame of the automobile, 3 the hood therefor, and 4 the radiator, of any ordinary or preferred construction. 5 is a casing or housing secured to the front of the radiator and provided with a comparatively large opening 6 having vertical guides 7 formed on each side thereof, said opening being substantially the full area of the front of the radiator. 8 is a plate, preferably of sheet metal, which is cut to form a helical coil 9 and is preferably composed of spring

material, such as steel, so that when the coil 55 is pulled out of the plane of the plate it will fly back to its normal position, flush with the plate, when released. The plate 8 is adapted to slide vertically in the guides 7 and has its lower end fitting within a horizontal groove 10 at the bottom of the opening. Normally, the helical coil will stand in the position shown in Fig. 1, with the coils in alinement and in the plane of the plate from which the coil is formed, but whenever desired, the coil may be pulled inward toward the radiator and thereby form air openings through which the currents of air may freely circulate for contact with the walls of the radiator.

The chamber 11 in the rear of the plate 8 is of suitable depth to allow the full opening of the coil and for the purpose of expanding the coil within the chamber I prefer to provide a lever 12 pivoted at 13 in the housing and having a hooked end 14 to engage a loop 15 formed on the inner end of the coil. The hook 14 is open at the top so that the loop 15 may be readily detached therefrom and the plate removed from the guides in operating the machine in warm weather or in case the coil or the plate should be damaged and it is desired to remove it and substitute another.

For operating the lever 12 from the driver's seat, I prefer to provide a wire 16 pivoted at 17 on the lever and extending back through the radiator to a toothed bar 18 that is mounted to slide through an opening in the dash 19 and engage a plate 20 thereon, 90 said bar having a suitable hand grip 21 for convenience in grasping and operating it. A series of notches are formed in the bar to allow for the desired adjustment of the spring and to admit fresh air to the chamber 11 it is only necessary to lift the bar and disengage it from the plate 20 and then pull it back sufficiently to allow the air to circulate freely through the coil and the chamber 11 and the radiator. When the bar is 100 disengaged from the plate 20 and released, the tension of the spring will return it to its normal position and thereby the air passages through the plate will be shut off. The coils of the spring are flat, as shown, 105 and may be of any suitable width, according to the volume of air it is desired to admit to the radiator and the degree of separation

of the coils will, of course, regulate the amount of air admitted to the chamber in front of the radiator.

To heat this chamber while the car or truck is not in use, I prefer to provide a lamp 22, using alcohol, gasoline or any other suitable liquid fuel, and I prefer to provide an electric igniter 23 adjacent to the wick of the lamp by means of which the driver of the car can produce a spark at the wick and ignite it whenever it is desired to heat the chamber 11. It will be understood, of course, that the helical coil may be projected in front of the plate instead of being thrown backwardly in the rear thereof within the chamber 11 by simply reversing the normal movement of the operating lever.

The connection 16 between the lever 12 and the bar 18 may be smaller where it passes through the radiator, if preferred, and may be sufficiently rigid so that it may be utilized to aid in closing the coil when the bar 18 is disengaged from the locking plate 20. This operating means, however, may be modified in many ways and I do not wish to be confined to the particular device employed, the broad idea of the invention being the helical or scroll spring device with a means for opening it to admit air to the chamber and the radiator.

I claim as my invention:

1. The combination, with a gas engine radiator, of a suitable housing mounted in front of the radiator and provided with an opening therein, a plate fitting said opening, said plate having a helical coil formed therein which, when opened, will admit a circulation of air to said housing and radiator, and means for opening said coil.

2. The combination, with a gas engine radiator and a housing in front of the same provided with an opening in its front wall, of a helical coil composed of spring material mounted to normally close said opening, said coil, when separated, admitting air to said housing and radiator, and means for opening said coil. 45

3. The combination, with an automobile gas engine and radiator, of a housing 50 mounted in front of the radiator and having an air intake opening, a coil of spring material mounted to normally close said opening, and means operable from the driver's seat for opening said coil to admit air to said housing and radiator. 55

4. The combination, with a gas engine radiator and a housing mounted in front of the same, of an expansible coil mounted in said housing to admit currents of air thereto 60 and to said radiator, and for shutting off the flow of such currents of air, and means for heating said housing and the walls of the radiator.

5. The combination, with an internal combustion engine radiator, of a housing mounted in front of the radiator and having an air intake opening and a coil mounted to normally close said opening, and means for expanding said coil to admit air through 65 70 said opening.

6. In combination, with a gas engine radiator, a plate mounted in front of said radiator and having a helical coil which, when open, will allow air to flow through said 75 plate to the radiator, and means for opening said coil.

In witness whereof, I have hereunto set my hand this 10th day of December, 1918.
EDWARD FERRISS.
